[57] CLAIM

The ornamental design for a magnetic actuator, as shown.

DESCRIPTION

FIG. 1 is a perspective view of the magnetic actuator;
FIG. 2 is a top plan view of the magnetic actuator;
FIG. 3 is a bottom plan view of a magnetic actuator;
FIG. 4 is a side elevational view of the magnetic actuator;
FIG. 5 is an elevational view of the opposite side of the
magnetic actuator as shown in FIG. 4;
FIG. 6 is a front elevational view of the magnetic actuator;
and,
FIG. 7 is a rear elevational view of the magnetic actuator.
